(57) **CLAIM**

The ornamental design of a water ride, as shown and described.

DESCRIPTION

FIG. 1 is a perspective view of a water ride showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The portions of the water ride shown in broken lines in FIGS. 1-7 do not form part of the claimed design. The dash-dot-dash lines shown in FIGS. 1-2 and 6-7 do not form part of the design and are included solely for the purpose of illustrating the boundary of the design.
